Atty.

UNITED STATES PATENT OFFICE

JOSEPH H. ALLEN, OF CHICAGO, ILLINOIS, ASSIGNOR TO INLAND GLASS WORKS, INC.,
OF CHICAGO, ILLINOIS, A CORPORATION OF ILLINOIS

ADVERTISING DEVICE

Application filed April 1, 1931. Serial No. 526,944.

This invention relates in general to display devices and has more particular reference to an illuminated globe or shade particularly well adapted for night advertising, as in shop windows, on store counters, etc. The device, however, is not restricted to interior advertising and in fact may be used outdoors for display purpose, as on the top of gasoline pumps at filling stations and other outdoor purposes.

10 In a device of this general character, it is usual to form an advertisement or other subject matter of display on the lamp shade or globe in such a way that the same is illuminated in an eye-arresting manner, so that the 15 attention of the casual observer will be attracted to the subject matter of display.

An important object of the present invention is to provide a device of the class described wherein advertisement or other subject 20 matter of display carried by the device may be quickly and easily changed, so as to give the device ready adaptability as an advertising medium.

In globes of this general character heretofore provided, it has been customary to form 25 the subject-matter of display permanently on the lamp shade, as by painting the sign directly on the glass of which the globe is usually formed, and then fusing the paints into 30 the glass by treatment. It has also been proposed to permanently paste signs upon the surface of the globe. In any event the devices heretofore provided have afforded no means for readily changing the advertisement 35 carried by the globe, and it is an important object of my present invention to form the globe so as to detachably receive a sign placard, containing a desired display subject matter thereon, so that the placard may be 40 readily demounted from or assembled in position in the globe.

Another object is to form the advertisement on a cheap sheet material so as to render the signs extremely inexpensive as far as the 45 individual advertisements are concerned, and hence to expand the utility of the device by making it possible to use the device inexpensively to display any number of different advertisements, the changeable feature having great advantages where the device is

used as an advertising medium. The possibility of employing the device in bringing a desired series or sequence of related advertisements before the observing public, it is thought, will be understood by those familiar 55 with the art of advertising.

Another object is to house the advertising placards within the lamp globe so that the same may be protected from dust and from dirt, and the weather, if the device is used 60 outdoors.

Numerous other objects and advantages will be understood from the following description, which, taken in connection with the accompanying drawing, discloses a preferred 65 embodiment of my invention.

Referring to the drawing:

Figure 1 is a perspective view, showing the front elevation of a display device embodying my invention, and

Figure 2 is a vertical section taken substantially along the line 2--2 of Figure 1.

To illustrate my invention, I have shown on the drawing a globe formed preferably of glass and having the so-called flattened or 75 canteen-shape. The opposed relatively flat faces 13 of the globe are adapted to form spaces in which the advertising or display subject-matter is adapted to be shown. The lamp shade or globe 11 has a relatively narrow neck 15 in its lower end, the same being adapted for engagement and support on a standard or base 17. A light producing source comprising, in the illustrated embodiment, an incandescent lamp 19 is supported 80 within the globe, as by the socket 21 carried by the base 17 and extending through the neck 15 of the globe. The flat faces 13 of the globe are preferably defined by inner grooves 23 formed in the globe itself in such a way as 85 to define internal pockets 25 on opposite sides of the globe. These pockets are adapted to detachably receive placards 27 to hold the same with their outer faces in contact with the inner surface of the flattened portions 13. 95 The flattened portions 13 are also preferably transparent, so that, when the lamp within the globe is illuminated, the display of subject matter 28, carried on the placards 27, will be clearly visible from outside the globe. 100

The remaining portions of the globe may be formed of opaque glass.

I am also able to obtain startling effects by slightly frosting the portions 13 behind which the cards are arranged. If the surfaces 13 are slightly frosted, the sign 28 will be quite invisible when the lamp 19 is dark, but will easily show through the frosting when the lamp is lighted. By alternately flashing the lamp on and off the advertising subject matter 28 contained on the cards 27 may be made to appear and disappear as if by magic.

The lamp 19 may be flashed by any suitable or convenient means, as by a manually or automatically operating switch in the power supply circuit 32. The flasher, however, is preferably of the automatic type and may be built directly into the lamp support base, as indicated at 33.

23 It is also possible to paint or otherwise form, preferably in a transparent medium or light colored paint, advertising matter 31 in the other surface of the portion 13, so that, when the lamp is off within the globe, this additional subject matter of display only will be visible to the observer.

As soon as the light 19 is illuminated, however, the message painted on the outside of the surface 13, being formed in relatively transparent media, will become invisible while the sign contained on the placard 27 will be made visible. Such a combination is of special utility where it is desired to present advertising in the form of questions and answers. The attention-getting questions may be formed in transparent media on the outer surface of the display portion 13, so that the attention of an observer will be drawn to the device, and the advertising answer to the question may be placed on the placard 27 within the globe, so that, when the light 19 is illuminated, the observer will be presented with the answer to the attention-arresting question, and in this way the desired advertising will be most successfully presented.

It is possible, by using the device heretofore described, to employ unique designs in the placard at minimum cost. Such designs may be formed on the card merely by printing, in the most inexpensive manner, so that the subject matter of display may be produced in large quantities.

The application of the placard requires no skill, since it is merely necessary to demount the globe from the standard and snap the placard in place with its edges lying in the retaining groove 23.

It is thought that the invention and numerous of its attendant advantages will be clearly understood from the foregoing description, and it is obvious that numerous changes may be made in the form, construction and arrangement of the several parts without departing from the spirit or scope

of my invention or sacrificing any of its attendant advantages; the form herein described being a preferred embodiment for the purpose of illustrating my invention.

Having thus described my invention, what I claim as new and desire to secure by Letters Patent, is as follow:

1. A display device comprising a glass lamp shade having a translucent display portion means forming subject-matter for display on the outer surface of said lamp shade and integral portions at the edges of said display portion and forming a groove on the inner side of the lamp shade for engaging and retaining the edge of a sign card carrying additional subject-matter for display within the lamp shade in order to retain the card against the inner side of the display portion in position to be viewed therethrough.

2. A display device comprising a glass envelope having a translucent display portion and an inwardly opening peripheral groove on the inner side of the envelope and bordering the edges of said display portion for engaging and retaining the edge of a sign card to retain the same within the envelope in position behind the display portion to be viewed therethrough.

3. A display device comprising a glass envelope formed with an inwardly opening circular groove on the inside of the envelope adjacent a display portion, behind which a member, carrying subject matter to be displayed, may be mounted in position to be viewed therethrough from outside the envelope by engaging the edges of the member within the groove.

4. A display device comprising a glass globe having a display portion and means formed in the globe for demountably securing a sign-carrying member carrying indicia for display behind said display portion, means forming an outer sign across said display portion in front of said sign-carrying member in position clearly visible from outside of the globe when the same is unlighted, said outer sign being formed in semi-transparent media whereby when the globe is internally illuminated the outer sign will seem to disappear and be replaced by the subject-matter of display contained in said member, and means forming a translucent film in front of the indicia of the sign-carrying member when mounted behind the display portion, the translucence of the film being such as to hide the indicia of the sign-carrying member from view through the display portion when the globe is not internally illuminated.

5. A display device comprising a glass envelope forming a lamp shade having a substantially circular cross-sectional configuration along one vertical axial plane and a substantially flattened or ovoidal cross-sectional

configuration in another vertical axial plane, said envelope being formed with an inwardly opening annular groove, on the inside of the envelope and extending in a plane substantially parallel with the plane of a medial, vertical section of the globe, for engaging and retaining the edge of a sign carrying member mounted within the lamp shade in order to secure the member within the shade with its sign-carrying surface against the inner surface of the display portion in position to be viewed therethrough.

6. A display device comprising a glass lamp shade having a translucent display portion, means forming subject-matter for display on the outer surface of said lamp, and integral inwardly extending portions at the edges of said display portion for engaging and retaining the edge of a sign card, carrying additional subject-matter for display, within the lamp lamp shade in order to retain the card against the inner surface of the display portion in position to be viewed therethrough and intermittently actuated light producing means within the shade.

7. A display device comprising a glass envelope adapted to contain a source of illumination and having a translucent display portion, means forming subject matter for display on the outer surface of said envelope and means forming an integral inwardly opening annular groove in said envelope bordering said display portion for engaging and retaining the edge of a sign card carrying additional subject matter for display within the envelope in position behind the display portion to be viewed therethrough from outside of the envelope.

In witness whereof, I have hereunto subscribed my name.

JOSEPH H. ALLEN.
